[57] **CLAIM**

The ornamental design for a spout, as shown and described.

DESCRIPTION

FIG. 1 is a perspective view of a spout showing my new design.

FIG. 2 is a front view thereof.

FIG. 3 is a side elevational view thereof, the opposite side being a mirror image of the side shown;

FIG. 4 is a rear view thereof.

FIG. 5 is a top view thereof.

FIG. 6 is a bottom view thereof.

FIG. 7 is a perspective view of a modified form of the spout shown in FIG. 1.

FIG. 8 is a front view of FIG. 7.

FIG. 9 is a side elevational view of FIG. 7, the opposite side being a mirror image of the side shown.

FIG. 10 is a rear elevational view of FIG. 7.

FIG. 11 is a top plan view of FIG. 7.

FIG. 12 is a bottom plan view of FIG. 7.

FIG. 13 is a perspective view of a second modified form of the spout shown in FIG. 1.

FIG. 14 is a front elevational view of FIG. 13.

FIG. 15 is a side elevational view of FIG. 13, the opposite side being a mirror image of the side shown.

FIG. 16 is a rear elevational view of FIG. 13.

FIG. 17 is a top plan view of FIG. 13.

FIG. 18 is a bottom plan view of FIG. 13.
